Primary Examiner — Susan Moon Lee(74) *Attorney, Agent, or Firm* — Panasonic Patent Center(57) **CLAIM**

I claim the ornamental design for a scanner, as shown and described.

DESCRIPTION

FIG. 1 is a front perspective view of a scanner of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

Broken lines and entirely unshaded portions contained within broken lines are not claimed.

1 Claim, 8 Drawing Sheets(56)
